PROCESS FOR REDUCING NITROANILINES

Harold Von Bramer, James E. Magoffin, and Milton Clemens, Kingsport, Tenn., assignors to Eastman Kodak Company, Rochester, N. Y., a corporation of New Jersey

Application April 16, 1948, Serial No. 21,428

7 Claims. (Cl. 260—580)

1

This invention relates to a process for preparing aromatic primary amines by the reduction of the corresponding aromatic nitro compounds.

It is known that aromatic nitro compounds can be either catalytically or chemically reduced to aromatic primary amines. The methods heretofore used for this purpose require long periods of time and yield products which usually are contaminated by impurities. In attempting to produce purer products it has been customary to purify the starting materials as thoroughly as possible before reduction. Even so, when strong acids, such as sulfuric acid, have been used, the resulting amine is discolored due to side-reactions. For example, when p-nitroaniline is made by the ammonolysis of p-chloronitrobenzene, before the p-nitroaniline is reduced to p-phenylenediamine, a purification of the p-nitroaniline is usually made to increase the yield and purity of product. One of the methods previously used comprises reducing the aromatic nitrocompound with iron and dilute hydrochloric acid. p-Phenylenediamine, for example, is usually made by the reduction of p-nitroaniline, which has been purified, by the action of iron filings and hydrochloric acid at temperatures of 80 to 100° C. The reaction is generally carried out in large tubs, equipped with heavy-duty agitators. Thus, only a portion of the p-nitroaniline can be charged at one time, the remainder being added from time to time as the reaction proceeds. Similarly, the iron filings cannot be added at one time, the remainder being gradually added over a period of time. Operating in this manner the reaction is slow and may require from 10 to 12 hours for completion. Moreover, the p-nitroaniline used in this process must be free from contamination, and the p-phenylenediamine produced must be recrystallized or vacuum distilled. Because of this inefficient method of production, p-phenylenediamine is an expensive chemical, and full use of its chemical potentialities as a raw material for synthesis is inhibited.

We have now found that aromatic primary amines can be prepared cheaply and in much less time than has been previously possible. We have further found that when the aromatic primary amines are to be produced by the reduction of aromatic nitro compounds in accordance with the process of our invention, it is unnecessary to first purify the aromatic nitro compound prior to reduction.

It is, accordingly, an object of our invention to provide a process for the production of aromatic primary amines. A further object is to provide

2

a process for reducing a nitro aromatic primary amine to an aromatic primary diamine. A still further object is to provide a process for reducing aromatic nitro compounds in about half the time, 5 or less, than has been previously necessary. Another object of our invention is to provide a process for reducing aromatic nitro compounds to the corresponding aromatic primary amines without first purifying the aromatic nitro compounds. 10 Other objects will become apparent from a consideration of the following description.

According to the process of our invention, we prepare aromatic primary amines by reducing aromatic nitro compounds without first purifying the 15 aromatic nitro compounds. Advantageously, our reduction can be carried out by passing superheated steam over the aromatic nitro compound, and introducing the resulting vapors of steam and the aromatic nitro compound into a reduction system. 20 We have found that when an aromatic nitro compound is reduced in this manner, the reduction takes place at the moment the aromatic nitro compound condenses in the reduction system, and the time consumed is only about half 25 that ordinarily required. The reaction mixture resulting from the reduction can then be used directly in the preparation of other compounds, as in the production of N-substituted compounds, or can be separated into its component parts by 30 any means known to the art.

Any aromatic nitro compound, which is volatile with steam and can be reduced to a substantially non-volatile aromatic primary amine can be used to advantage in practicing the process of our invention. Especially useful are the mononuclear aromatic nitro compounds, such as p-nitrophenyl compounds, etc. Typical aromatic nitro compounds include: nitrobenzene, o-, m-, and p-chlorobenzene, o-, m-, and p-nitrophenols, o-, m-, 35 and p-nitrotoluenes, o-, m-, and p-nitroanilines, 40 3-, 4-, 5-, and 6-nitro-o-toluidines, 2-, 4-, 5-, and 6-nitro-m-toluidines, 2-, and 3-nitro-p-toluidines, α - and β -nitronaphthalenes, 4-nitro-1-naphthylamine, 1-nitro-2-naphthylamine, etc.

45 The following description will serve to illustrate the manner whereby we prepare one of the primary amines, p-phenylenediamine, which can conveniently be prepared according to the process of our invention.

50 The accompanying drawing illustrates, schematically, apparatus suitable for carrying out our invention in one of its embodiments. The drawing shows a still 10 equipped with a feed line 11 supplied with a shut-off valve. The still is connected with an ejector 12 which is connected to

a conduit 13 which leads to a reservoir 14. A line 15 extends from the bottom of the reservoir to a pump 16 which drives liquids through a line 17 back to the ejector 12 and thence to the reservoir 14, so that a circulating stream of liquids can be maintained. Extending from the line 17 between the pump 16 and the ejector is a take-off line 18 equipped with a shut-off valve which leads to a filter 19. From the top of the reservoir 14 a conduit 20 leads to a cyclone-type separator 21 which feeds back any small amounts of p-nitroaniline and p-phenylenediamine (or other aromatic nitro compound) vaporized or entrained with the water from the reservoir, through a conduit 22. The top of the cyclone separator is connected by a line 23 to a steam-jet ejector 24 which serves to draw a vacuum on the reservoir.

In accordance with one embodiment of our invention, 13.13 pounds of crude p-nitroaniline, which was conveniently prepared by the ammonolysis of p-ch'oronitrobenzene and contained water and other impurities, were fed into the still 10 through the inlet line 11. Cold water was then added to the conduit 13 by a line (not shown), and then circulated through the reservoir 14 to the pump 16 through the discharge line 15, and from the pump to the ejector 12 through the discharge line 17 of the pump. The circulation of the cold water through the ejector 12 was sufficient to create a vacuum of about 15 inches of mercury in the still 10, and this was adjusted to about 2 to 5 inches of mercury by the addition of air to the still through the inlet line 11. The still was then slowly heated, and the removal of water from the crude p-nitroaniline was quite rapid. After the temperature reached 150° C., removal of water was substantially complete. The water circulating through the ejector 12 was then heated to about 85° C., and 1.465 pounds of iron dust and 0.0182 pound of sulfuric acid, per pound of p-nitroaniline in the still 10, were added to the water circulating through the ejector 12. The air vent (not shown) to the still was closed, and steam superheated to a temperature of about 200° C. was passed over the dried, molten p-nitroaniline and thence to the ejector 12. While the temperature of the still-pot 10 remained at 190 to 200° C., distillation occurred, and a mixture of water and p-nitroaniline vapors, in a ratio of approximately 25 to 1 passed from the still through the ejector 12 and into the conduit 13. Both the water and p-nitroaniline vapors were condensed by the rapidly moving stream in the conduit 13, and the p-nitroaniline was immediately reduced by the iron dust to p-phenylenediamine. The concentration of water in the circulating steam in the conduit 13 was kept substantially constant by passing steam through the ejector 24 thus creating a vacuum in the reservoir 14, which caused rapid removal of water through the line 20 connected to the cyclone separator 21. Any small amounts of p-nitroaniline and p-phenylene-diamine vaporized or entrained were condensed in the separator 21 and returned to the reservoir 14 by the line 22 connected to the bottom of the separator, while the water vapors escaped from the top of the separator through a line connected to the ejector 24.

After all of the p-nitroaniline had been distilled from the still 10, the volume of liquid in the conduit 13, reservoir 14, and the connecting lines 15 and 17, was adjusted by the addition of water (or evaporation by means of the steam-jet ejector 24 when too much water was in the sys-

tem) until a free-flowing mass was obtained which could be easily handled. The sulfate ions dissolved in the liquor were removed by careful neutralization with barium hydroxide, and while the reaction slurry was still hot it was passed from the circulating stream in the line 17 through the discharge line 18 into the filter 19 where all of the iron oxide and barium sulfate were removed. The filtrate consisted of a clear, hot solution of p-phenylenediamine which could conveniently be used directly in the preparation of other compounds, if desired.

In order to obtain pure p-phenylenediamine, the liquor containing the p-phenylenediamine was cooled slowly with constant agitation, so that uniform crystals of p-phenylenediamine were produced. When crystals no longer formed, the slurry was centrifuged in an inert atmosphere, e. g., nitrogen, and then conveyed from the centrifuge to a vacuum drying apparatus, where all water was removed. There were thus obtained 9.8 pounds, representing a yield of 96%, of p-phenylenediamine in the form of a powder, which darkened only slightly when exposed to the air.

The mother liquor from the centrifuging operation can be returned to the reduction system as a part of the charge for the next reduction, or it can be conveyed to an evaporator where it can be concentrated. The concentrated solution can then be allowed to crystallize, and a second crop of p-phenylenediamine crystals obtained. This mother liquor is also suitable for any use where an aqueous solution of p-phenylenediamine is acceptable.

While the above example described the preparation of p-phenylenediamine, it is to be understood that other aromatic primary amines can be prepared equally well. Likewise, the conditions used in our process can be varied widely, and depend largely on the properties of the nitro compound being reduced. For example, the reduced nitro compound need not be separated from the reduction system in the manner described above, but can be separated by any of the methods known to those skilled in the art (e. g. extraction, crystallization, distillation, decantation, etc.). For some purposes it is not necessary to treat the reduction liquor further since the untreated liquor is useful for the further synthesis of other organic compounds, e. g. the N-substituted amines, dyes, etc.

The amount of metallic iron and sulfuric acid used in the reduction of the nitro compound can also be varied. By suitable adjustment of the concentration of the sulfuric acid and using an iron dust of proper activity, it is possible to reduce the nitro compound substantially as fast as it is condensed in the reduction system. When p-nitroaniline was reduced, it was found that best results were obtained when 1.465 pounds of iron and 0.0182 pound of sulfuric acid were used for each pound of p-nitroaniline reduced. The pH of the reduction liquor is a wandering figure without significance, varying from strongly acid to weakly basic as the reduction proceeds. The pH can be maintained at any desired figure by the addition of more acid as the reaction progresses.

The temperatures used in the various steps of our process can be varied considerably and are generally a function of the nitro compound being reduced. For the reduction system we have found that a temperature of about 85° C. gives the best results, however, temperatures from

60-90° C. can be used, if desired. Similarly, when steam superheated to a temperature of about 200° C. is used, the temperature in the still 5 remains at about 190 to 200° C. and the distillation of the nitro compound into the reduction system is more efficient. This temperature of the steam can be varied widely, however, depending upon the temperature at which the various nitro compounds become volatile with steam. Temperatures of from 150 to 350° C. can be used, although temperatures of from 175 to 225° C. are generally sufficient.

Mineral acids other than sulfuric acid have been found to be useful in the practicing the process of our invention. Typical acids include sulfuric acid, hydrochloric acid, phosphoric acid, etc. Likewise, metals other than iron can be used. We have found that aluminum is especially useful where iron is not easily available.

While the process of our invention is particularly useful in the reduction of crude or unpurified aromatic nitro compounds, it is likewise useful for reducing pure compounds, since not only are the yields higher, and the time required for reduction much less, but the aromatic primary amines produced are much purer and darken only slightly when exposed to air. The products of the prior art processes, on the other hand, are darker, probably due to the large contact time necessary to complete reduction, and usually must be recrystallized or otherwise purified before use.

It is to be understood that the drawing appended hereto is merely a schematic diagram of our invention, and that various modifications thereof can be made by those skilled in the art without departing from the spirit and scope of our invention.

What we claim and desire to secure by Letters Patent of the United States is:

1. In a process for reducing a nitroaniline to a phenylenediamine, the steps which comprise passing steam heated from 150° C. to 350° C. over the nitroaniline, and introducing the resulting vapors of steam and the nitroaniline into a reducing system, consisting of an aqueous mineral acid selected from the group consisting of sulfuric acid, phosphoric acid and hydrochloric acid and metallic iron, and maintained at a temperature of from 60° C. to 90° C. where the said vapors are condensed and the nitroaniline contained in the steam distillate is reduced to a phenylenediamine.

2. In a process for reducing a nitroaniline to a phenylenediamine, the steps which comprise passing steam heated from 150° C. to 350° C. over the nitroaniline, and introducing the resulting vapors of steam and the nitroaniline into a reducing system, consisting of aqueous sulfuric acid and metallic iron, and maintained at a temperature of from 60° C. to 90° C. where the said vapors are condensed and the nitroaniline contained in the steam distillate is reduced to a phenylenediamine.

3. In a process for reducing a nitroaniline to a phenylenediamine, the steps which comprise passing steam heated from 150° C. to 350° C. over the nitroaniline, and introducing the resulting vapors of steam and the nitroaniline into a reducing sys-

tem, consisting of aqueous phosphoric acid and metallic iron, and maintained at a temperature of from 60° C. to 90° C. where the said vapors are condensed and the nitroaniline contained in the steam distillate is reduced to a phenylenediamine.

4. In a process for reducing a nitroaniline to a phenylenediamine, the steps which comprise passing steam heated from 150° C. to 350° C. over the nitroaniline, and introducing the resulting vapors of steam and the nitroaniline into a reducing system, consisting of aqueous hydrochloric acid and metallic iron, and maintained at a temperature of from 60° C. to 90° C. where the said vapors are condensed and the nitroaniline contained in the steam distillate is reduced to a phenylenediamine.

5. In a process for reducing p-nitroaniline to p-phenylenediamine, the steps which comprise passing steam heated from 175° C. to 225° C. over p-nitroaniline, introducing the resulting vapors of steam and p-nitroaniline into a circulating stream, consisting of aqueous sulfuric acid and metallic iron, and maintained at a temperature of from 60° C. to 90° C. where the said vapors are condensed and the p-nitroaniline in the steam distillate is reduced to p-phenylenediamine.

6. In a process for reducing p-nitroaniline to p-phenylenediamine, the steps which comprise passing steam heated from 175° C. to 225° C. over p-nitroaniline, introducing the resulting vapors of steam and p-nitroaniline into a circulating stream, consisting of aqueous phosphoric acid and metallic iron, and maintained at a temperature of from 60° C. to 90° C. where the said vapors are condensed and the p-nitroaniline in the steam distillate is reduced to p-phenylenediamine.

7. In a process for reducing p-nitroaniline to p-phenylenediamine, the steps which comprise passing steam heated from 175° C. to 225° C. over p-nitroaniline, introducing the resulting vapors of steam and p-nitroaniline into a circulating stream, consisting of aqueous hydrochloric acid and metallic iron, and maintained at a temperature of from 60° C. to 90° C. where the said vapors are condensed and the p-nitroaniline in the steam distillate is reduced to p-phenylenediamine.
